**DETERGENT COMPOSITIONS CONTAINING
BUILDERS AND A UREA-OLEFINE-SUL-
FURIC ACID CONDENSATION PRODUCT**

Thomas J. Galvin and Francis A. Hughes, Wilmington, Del., assignors to Atlas Chemical Industries, Inc., Wilmington, Del., a corporation of Delaware
No Drawing. Filed Oct. 21, 1965, Ser. No. 500,256
7 Claims. (Cl. 252—137)

ABSTRACT OF THE DISCLOSURE

Detergent compositions comprising an inorganic detergent builder and a water-soluble salt of an urea-olefin-sulfuric acid condensate. The olefin is either butadiene or a mixture of a major amount of butadiene and a minor amount of cyclopentadiene, unhindered tertiary mono-olefin, 2-alkyl-1,3-butadiene, or mixtures thereof. The condensate may be prepared by adding the olefin to a suspension of urea and sulfuric acid in an inert solvent at a temperature from —10° C. to 70° C.

This invention relates to synthetic detergent compositions, and more particularly concerns synthetic detergent compositions comprising urea-olefin-sulfuric acid condensates.

Synthetic detergent compositions have been known for many years, and, at present, the most widely used and versatile synthetic detergents in commercial use are the branched chain alkyl benzene sulfonates (ABS). It has been estimated that about 75% of all household detergents contain some ABS. These ABS detergents are usually compounded with alkaline builders and frequently contain additives such as brighteners, antiredeposition agents, foaming agents, wetting agents, ion sequestering agents, and the like, to give "built" or "compounded" synthetic detergents.

One drawback to the use of ABS is the difficulty of getting rid of the compound after it has performed its job. Disposal of ABS in sewage, rivers, or ground waters can cause pollution because the ABS is not readily biologically degraded and is not readily precipitated by common chemical coagulants used in sewage treatment. Most organic matter contained in sewage is readily degraded to harmless, low molecular weight compounds by bacteria contained in the sewage but ABS resists the attack of the bacteria. In many sewage treating plants chemical coagulants are employed to flocculate undesirable matter from the water which is removed by settling or filtering. ABS resists the action of these chemical coagulants (ferric chloride, ferric sulfate, ferrous sulfate, lime, alum, etc.) and continues through the sewage treating plant into the effluent causing undesirable foaming. Over the past decade, tremendous efforts have been directed toward the discovery of a synthetic detergent which is comparable in detergents characteristics to ABS but which can be readily disposed of after it has performed its job.

It is an object of the present invention to provide detergents which have high detergents characteristics. It is another object of the present invention to provide detergents which are more biodegradable than ABS. It is another object of the present invention to provide detergents which can easily be caused to precipitate from aqueous solutions. It is another object of the present invention to provide detergents which do not cause foam problems. It is another object of the present invention to provide detergents which are economically feasible. It is another ob-

2

ject of the present invention to provide detergents which are non-toxic and non-irritating.

Other objects and advantages of this invention will further become apparent in the following description and in the appended claims.

It has now been discovered that the foregoing objects are accomplished by a detergent composition which comprises at least one water-soluble salt of an urea-olefin-sulfuric acid condensation product and at least one builder.

The condensation products of the present invention are condensates of urea, sulfuric acid, and olefin, wherein the olefin is either 1,3-butadiene or a mixture of a major amount of 1,3-butadiene and a minor amount of cyclopentadiene, unhindered tertiary mono-olefin, 2-alkyl-1,3-butadiene, or mixtures thereof, preferably at least 75 mole percent of the olefin being 1,3-butadiene.

The term "unhindered tertiary mono-olefin" as used herein denotes tertiary mono-olefins in which carbon atoms alpha, beta, and gamma to the tertiary olefinic carbon atom are free of side chain carbon. The unhindered tertiary mono-olefin can be isobutylene, 2-methyl-1-pentene, 2-methyl-2-butene, 2-methyl-1-butene, 2-methyl-2-pentene, 3-methyl-2-pentene, 2-methyl-1-hexene, 2-methyl-2-hexene, and the like. The preferred unhindered tertiary mono-olefin being isobutylene. The 2-alkyl-1,3-butadiene is one wherein the alkyl group is unbranched and contains from 1 to 3 carbon atoms, such as 2-methyl-1,3-butadiene (isoprene), 2-ethyl-1,3-butadiene, and 2-propyl-1,3-butadiene. The preferred 2-alkyl-1,3-butadiene is isoprene.

Although the amounts of urea, olefin, and sulfuric acid used to prepare the condensation products can vary widely, the preferred condensates are those which contain on an average, per urea residue, from about 2 to about 50 diolefin residues, from about 0.1 to about 1.5 sulfate groups, and from about 0.1 to about 10 carbon to carbon double bonds.

These condensation products are used in the present invention in the form of their water-soluble salts. Of these, the alkali metal (e.g. sodium and potassium) and ammonium salts are preferred though other salts, such as amine and alkanol amine, can be used if desired.

The condensation products of the present invention and suitable methods for their preparation are fully described in copending application Ser. No. 419,201, filed Dec. 17, 1964, the disclosure of which is incorporated herein by reference. Briefly, the condensation products are prepared by reacting 1,3-butadiene, alone or in admixture with a 2-alkyl-1,3-butadiene, cyclopentadiene, or an unhindered tertiary mono-olefin, with a solution or suspension of urea in concentrated sulfuric acid and neutralizing the resulting sulfated product.

In addition to the above-described water-soluble condensation products, the detergent compositions of the present invention contain at least one inorganic detergent builder. The term "inorganic detergent builder" is well known in the art and refers to various inorganic compounds which promote detergent action. Builders which are in use today and which can be used in the detergent compositions of the present invention include alkali metal carbonates such as sodium carbonates, alkali metal bicarbonates, condensed phosphates such as potassium pyrophosphate and sodium polyphosphate, silicates such as sodium silicate and the like. Additives such as water softeners, wetting agents, ion sequestering agents, optical brighteners or chemical bleaching agents, antiredeposition agents such as carboxymethyl cellulose and sodium carboxymethyl cellulose, foaming agents, and the like can also be used. The specific builders and additives and

the amounts thereof employed in the detergent composition of the present invention can vary widely and depend to a great extent on economic considerations and on the particular conditions under which the detergent compositions are to be utilized. Excellent results may be obtained with detergent compositions containing a major amount of builder and a minor amount of butadiene condensate.

The detergent compositions of the present invention can be used as solid detergent or in liquid formulations.

The following examples illustrate the manner in which the invention may be practiced, but it is to be understood that such details are given merely for exemplification purposes and are not to be construed as limiting the scope of the appended claims. Unless otherwise indicated, the proportions are expressed in parts by weight. Numbered examples are in accordance with the invention, those designated by letter are inserted for purposes of comparison.

Example I

15 parts sodium salt of a condensation product of 3 moles of butadiene, 1 mole of urea, and 1.5 moles of sulfuric acid and having an acid number of 14, an iodine number of 132, a melting point of 105-114° C., 4.96% nitrogen, and 5.24% sulfur are blended with 35 parts sodium tripolyphosphate, 10 parts sodium metasilicate, 39 parts sodium carbonate, and 1 part sodium carboxymethyl cellulose to a fine powder in a Waring Blender.

The detergency of this blend was tested in 0 and 100 parts per million water hardness (parts per million as Ca CO_3 with 60% as Ca and 40% as Mg) in a Baker Terg-O-Tometer at 120° F. and 60 r.p.m. using American Conditioning House #119 soiled cloth. The concentration of the detergent composition was 0.25 weight percent. Swatches after washing were dried at 185° F. for one hour followed by conditioning for 24 hours in a constant temperature and humidity room (75° F., 40% R. H.) before reflectance measurements were run.

The wash cycle consisted of placing four swatches (4 x 4 inch) in the preheated detergent (one liter volume), washing for 15 minutes followed by two separate 3 minute rinses. Calculations were:

Percent Increase in Reflectance=

$$\frac{\text{Washed Swatch R} - \text{Original R}}{\text{Original R}} \times 100$$

where R=reflectance of swatch

Example A

Example I was repeated using a branched chain sodium dodecylbenzene-sulfonate (abbreviated hereinafter as SDBS), one of the best detergents in commercial use, in place of the urea-butadiene-sulfuric acid condensate.

Example II

Example I was repeated except that a mixture of 3 moles butadiene and 1 mole isobutylene was substituted for 3 moles of butadiene therein recited. The condensation product after neutralization with sodium hydroxide had an acid number of 1.7, an iodine number of 155, a melting point of 58-62° C., 3.65% nitrogen, and 4.3% sulfur.

Example III

Example I was repeated except that a mixture of 3.6 moles butadiene and 0.4 mole isobutylene was substituted for the 3 moles of butadiene therein recited. The condensation product after neutralization with sodium hydroxide had an acid number of 8.6, an iodine number of 171, a melting point of 59-62° C., 3.3% nitrogen and 4.8% sulfur.

Example B

Example I was repeated except that the urea-butadiene-sulfuric acid condensate as omitted.

The percent increase in reflectance obtained in Examples I, II, III, A, and B are shown in Table I.

TABLE I

Example No.	Percent Increase in Reflectance	
	0 p.p.m. Water Hardness	100 p.p.m. Water Hardness
I	143	99
A	135	94
II	141	97
III	139	101
B	100	49

Example IV

15 parts sodium salt of a condensation product of 3 moles of butadiene, 1 mole of urea, and 1.5 moles of sulfuric acid and having an acid number of 14, an iodine number of 132, a melting point of 105-114° C., 4.96% nitrogen, and 5.24% sulfur are blended with 35 parts sodium tripolyphosphate, 10 parts sodium metasilicate, 39.5 parts sodium carbonate, and 0.5 parts sodium carboxymethyl cellulose to a fine powder in a Waring Blender.

The detergency of this blend was tested in a Baker Terg-O-Tometer using American Conditioning House #115 cotton soiled cloth. The concentration of the detergent composition was 0.25 weight percent. The increase in reflectance was 130.2%.

Example C

Example IV was repeated using SDBS in place of the urea-butadiene-sulfuric acid condensate. The increase in reflectance was 130.8%.

Example V

Example IV was repeated except that the carboxymethyl cellulose was replaced by sodium carbonate and the concentration of the detergent composition was 1.0% by weight. The increase in reflectance was 117.3%.

Example VI

Example V was repeated using the ammonium salt of the urea-butadiene-sulfuric acid condensate instead of the sodium salt. The increase in reflectance was 115.6%.

Example D

Example V was repeated using SDBS instead of the urea-butadiene-sulfuric acid condensate. The increase in reflectance was 111.9%.

Thus, it is readily apparent from Example I-VI and A-D, that the detergency of the present urea-olefin-sulfuric acid condensation products is equivalent or sulfuric acid condensation products is equivalent or superior to SDBS, one of the most widely used detergents presently in commercial use. In addition to having excellent detergency characteristics, these condensation products are also less toxic, less irritating and are more readily precipitated by common chemical coagulants, used in sewage treatment than is SDBS.

The results of toxicological studies on the detergents are shown in Table II, below. The acute oral toxicity was run on mice according to the method of Weil, Litchfield, and Wilcoxon, Biometrics, vol. 8, pp. 249-262 (1952), and the Journal of Pharmacology and Experimental Therapeutics, vol. 95, pp. 99-113, (1949). Category of the compounds was judged according to the terminology of Hodge and Sterner, Industrial Hygiene Quarterly, vol. 10, pp. 93-96, (1949). Primary irritation to rabbit skin and eye was determined according to the procedure outlined in "Appraisal of the Safety of Chemicals in Foods, Drugs and Cosmetics," Association of Food and Drug Officials, U.S. (1959), pp. 46 and 49. A 60% aqueous solution of the detergents were employed. The interpretation of scoring of irritation to the eye was made according to Kay and Calandra, Journal of the Society of Cosmetic Chemists, pp. 285-286 (1962).

TABLE II.—TOXICOLOGICAL PROPERTIES OF THE DETERGENTS

Detergent	Acute Oral Toxicity		Primary Irritation to Rabbit Skin	
	LD 50 g. kg. Body Weight	Category of Compound	Irritation Index	Degree of Irritation
SDBS.....	2.24	Slightly toxic.	5.58	Severe.
Butadiene-urea-sulfuric acid sodium salt.	7.4	Practically non-toxic.	0.34	Mild.
Butadiene-isobutylene (3:1)-urea-sulfuric acid sodium salt.	19.9	Relatively harmless.	0.25	Do.
Butadiene-isobutylene (9:1)-urea-sulfuric acid sodium salt.	22.4	.....do.....	0.08	Do.

The condensation products of the present invention are readily precipitated by flocculants such as ferric chloride and/or by contact with soil as illustrated in Table III, below. An aqueous solution of 5 p.p.m. detergent was mixed with the indicated amount of $\text{FeCl}_3 \cdot 6\text{H}_2\text{O}$ and/or Delaware soil. The slurries were filtered after 24 hours and the amount of detergent in the filtrate determined by the standard Methylene Blue Method (Standard Methods for the Examination of Water and Waste Water, 11th edition, American Public Health Association, Inc., pp. 246-248).

TABLE III.—REMOVAL OF DETERGENTS FROM AQUEOUS SOLUTIONS BY COAGULANT

Detergent	FeCl ₃ ·6H ₂ O Added	p.p.m. Soil Added	Percent Detergent Removed
Butadiene-urea-sulfuric acid sodium salt.....	0	0	0
SDBS.....	0	0	0
Butadiene-urea-sulfuric acid sodium salt.....	5	0	39
SDBS.....	5	0	24
Butadiene-urea-sulfuric acid sodium salt.....	10	0	64
SDBS.....	10	0	39
Butadiene-urea-sulfuric acid sodium salt.....	15	0	67
SDBS.....	15	0	42
Butadiene-urea-sulfuric acid sodium salt.....	0	1,000	30
SDBS.....	0	1,000	4
Butadiene-urea-sulfuric acid sodium salt.....	10	1,000	74
SDBS.....	10	1,000	7

The detergents of the present invention have a biological oxygen demand value which indicates that they are being degraded whereas SDBS has a zero BOD which indicates no degradation.

The biological oxygen demands of the urea-olefin-sulfuric acid condensation products of the present invention are shown in Table IV.

TABLE IV.—BIOLOGICAL OXYGEN DEMAND OF DETERGENTS

Seed	Days incu- bation	Mg. Deter- gent Used	Biological Oxygen Demand as mg. O ₂ per mg. detergent			
			SDBS ¹	B-U ²	B-I-U ³ (3:1)	B-I-U ⁴ (9:1)
24 hour old sewage.....	{ 3 5	1.0 2.5	0 0	.03 .03	.02 .03	.04 .02
2 week old sewage.....	{ 11 5	1.0 2.5	0 0	.05 .03	.06 .04	.04 .05

¹ Sodium dodecylbenzene sulfonate.

² Sodium salt of butadiene-urea-sulfuric acid condensate.

³ Sodium salt of butadiene-isobutylene-urea-sulfuric acid condensate containing three moles butadiene per mole of isobutylene.

⁴ Sodium salt of butadiene-isobutylene-urea-sulfuric acid condensate containing nine moles butadiene per mole of isobutylene.

Thus, it has been established that the detergent compositions of the present invention have excellent detergents characteristics, are non-toxic and non-irritating, and easily precipitated from aqueous solutions.

The most appropriate builder or mixture of builders, their proportion to each other, and their concentration in each detergent composition may be suitably determined by routine controls since the beneficial results vary to some degree with changes in formulations. In each case, the proper washing conditions and the intended use of the detergent compositions (e.g. hard or soft water, general home or commercial use, shampoos, machine wash-

ing, etc.) should be taken into consideration in order to derive the maximum beneficial results. The particular builders and the amounts thereof can vary widely and form no part of the present invention that condensation products of urea, sulfuric acid, and butadiene, alone or in admixture with minor amounts of an unhindered tertiary mono-olefin, cyclopentadiene, or 2-alkyl butadiene, can be blended with various builders, to yield a novel and highly-desirable detergent composition.

Although the present invention has been described with reference to particular embodiments and examples, it will be apparent to those skilled in the art that variations and modifications of this invention can be made and that equivalents can be substituted therefor without departing from the principles and true spirit of the invention:

Having described the invention, what is desired to be secured by Letters Patent is:

1. A detergent composition consisting essentially of a major amount of inorganic detergent builder and a minor amount of water-soluble salt of an urea-olefin-sulfuric acid condensation product, said condensation product being prepared by (1) forming a suspension of urea and from 0.75 to 3.0 molar proportions of a sulfuric acid solution containing from 85 to 105 percent by weight of equivalent H_2SO_4 in an inert organic diluent; (2) introducing into the said suspension, at with continuous agitation and a temperature of from -10°C . to 70°C ., from 0.8 to 10 molar proportions of an olefin selected from the group consisting of 1,3-butadiene and a mixture of a major proportion of 1,3-butadiene and a minor proportion of a member selected from the group consisting of cyclopentadiene, unhindered tertiary mono-olefins, and 2-alkyl 1,3-butadienes wherein the alkyl radical is unbranched and contains from 1 to 3 carbon atoms; (3) and recovering the condensation product from the reaction

45 mixture, all of said molar proportions being per molar proportion of urea.

2. The detergent composition of claim 1 wherein the water-soluble salt of an urea-olefin-sulfuric acid condensation product is an alkali metal salt or an ammonium salt.

3. The detergent composition of claim 2 wherein the olefin is a mixture of 1,3-butadiene and isobutylene containing about three mols of butadiene per mol of isobutylene.

75 4. The detergent composition of claim 2 wherein the olefin is a mixture of 1,3-butadiene and isobutylene con-

taining about nine mols of 1,3-butadiene per mol of isobutylene.

5. The detergent composition of claim 2 wherein the inorganic detergent builder is selected from the group consisting of alkali metal carbonates, alkali metal bicarbonates, alkali metal condensed phosphates, alkali metal silicates, and mixtures thereof.

6. A detergent composition consisting essentially of an alkali metal polyphosphate, an alkali metal carbonate, an alkali metal silicate, an alkali metal carboxymethylcellulose, and a compound selected from the group consisting of alkali metal salts and ammonium salts of an urea-olefin-sulfuric acid condensation product prepared by (1) forming a suspension of urea and from 0.75 to 3.0 molar proportions of a sulfuric acid solution containing from 85 to 105 percent by weight of equivalent H_2SO_4 in an inert organic diluent; (2) introducing into the said suspension, with continuous agitation and at a temperature of from $-10^\circ C.$ to $70^\circ C.$, from 0.8 to 10 molar proportions of an olefin selected from the group consisting of 1,3-butadiene and a mixture of a major proportion of 1,3-butadiene and a minor proportion of a member selected from the group consisting of cyclopentadiene, unhindered tertiary mono-olefins, and 2-alkyl 1,3-butadienes wherein the alkyl radical is unbranched and contains from 1 to 3 carbon atoms; (3) and recovering the

condensation product from the reaction mixture, all of said molar proportions being per molar proportion of urea.

7. The detergent composition of claim 6 consisting essentially of about 35 parts sodium polyphosphate, about 39 parts sodium carbonate, about 10 parts sodium silicate, about 1 part sodium carboxymethylcellulose, and about 15 parts sodium salt of the condensation product, said condensation product being prepared with about four mols of 1,3-butadiene, about 1 mol of urea, and about 1.5 mols of sulfuric acid.
